(57) **CLAIM**

The ornamental design for a linear actuator, as shown and described.

DESCRIPTION

FIG. 1 is a front right perspective view of a linear actuator in accordance with a first embodiment of our new design when in an extended state;

FIG. 2 is a right side elevational view thereof;

FIG. 3 is a front elevational view thereof;

FIG. 4 is a left side elevational view thereof;

FIG. 5 is a rear elevational view thereof;

FIG. 6 is a top plan view thereof;

FIG. 7 is a bottom plan view thereof;

FIGS. 8-14 are views that correspond to FIGS. 1-7 when the linear actuator is in a retracted state;

FIG. 15 is a front right perspective view of a linear actuator in accordance with a second embodiment of our new design when in an extended state;

FIG. 16 is a right side elevational view thereof;

FIG. 17 is a front elevational view thereof;

FIG. 18 is a left side elevational view thereof;

FIG. 19 is a rear elevational view thereof;

FIG. 20 is a top plan view thereof;

FIG. 21 is a bottom plan view thereof; and,

FIGS. 22-28 are views that correspond to FIGS. 15-21 when the linear actuator is in a retracted state.

The broken lines in the figures are directed to environment and are for illustrative purposes only and form no part of the claimed design.
